UNITED STATES PATENT OFFICE.

ERNEST A. BOHLMAN, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

MULTIPLE CONTROL.

Application filed May 22, 1926. Serial No. 110,899.

My invention relates to tuning couplers or transformers as are used in wireless telegraph or telephone receiving systems, and resides in a novel method of construction 5 and operation of the same.

A feature of my invention resides in a multiple control arrangement for such devices.

Another feature of my invention has to 10 do with the manner in which the coils are mounted and associated with one another, and the construction and control of the apparatus by which the inductances of the secondaries of the transformers or couplers 15 are varied in steps by means of a single control arrangement.

Another feature of my invention has to 20 do with the manner in which the inductance within the steps is varied by means of a separate single control unit.

Another feature of my invention has to 25 do with the manner in which the contact or wiper arms for varying the inductance of the transformers by steps are associated with the control arrangement.

A still further feature of my invention 30 is the manner in which the rotary supports within the stator supports are held in position, and the novel means which are provided for leading the terminal ends of rotary coils to terminals which are adapted to receive connections from an external circuit.

A further feature of my invention is the 35 novel shielding means which are provided for shielding the transformers and the means for securing the same in position.

A still further feature of my invention is the provision of a novel wiper arrangement 40 in association with a conducting element to provide means for connecting the wiper with an external circuit.

The above features as well as others not 45 specifically pointed out will be more fully described and explained in the following specification and for a more complete understanding of my invention reference may be had to the accompanying drawings in which like references in the several views denote like parts and in which:

50 Fig. 1 is a top view of the apparatus comprising my invention in association with a mounting panel and mounting base.

55 Fig. 2 is a front view of Fig. 1 with the mounting panel removed and the front of the shielding members cut away.

Fig. 3 is a sectional view along the line 3—3 of Fig. 1 which clearly illustrates the means for controlling the rotor elements of the transformers.

Fig. 4 is a sectional view along the line 4—4 of Fig. 1 which clearly illustrates the means that controls the wipers which engage contacts associated with the tapped secondaries of the transformers.

Fig. 5 is a sectional view through one of 65 the transformers to illustrate the means for carrying the terminals of the rotor winding to external terminals.

Fig. 6 is a sectional view along the line 6—6 of Fig. 1.

Fig. 7 is a fragmentary view of the wiper 70 and arm of a switch unit illustrating their association with the shaft to which they are secured.

Referring now particularly to Fig. 1 the 75 devices or transformers T, T', T², T³ are each provided with a cylindrical frame or stator tube, 2, 3, 4 and 5 respectively and mounted within the stator tubes are rotatable cylindrical frames or rotor tubes 6, 7, 80 8 and 9 shown in dotted lines in Fig. 1. The stator coils 2, 3, 4 and 5 are mounted upon a base board 10 by brackets and as each of the stator coils is mounted in a similar manner a description of one will 85 suffice. A U-shaped bracket 11 is provided with diverging legs 12 and 13 which are provided with tapped orifices 14, and screws 15 which pass through suitable orifices in the stator tube 2 near its peripheral edge 90 have threaded engagement with the tapped orifices 14 in the respective legs 12 and 13 of the bracket 11 to secure the stator tube 2 to the bracket 11, the brackets 11 being in turn secured to the base board 10 by means 95 of screws 11'.

The rotor tubes 6, 7, 8 and 9 are supported on a rod 16 of suitable insulating material such as bakelite and as the rotor elements are supported on the rod 16 in a similar 100 manner a detailed description of one will suffice. The rotor element or tube 6 is provided with a pair of orifices 17 and 18 diametrically opposite which are adapted to receive the sleeve extensions 19 of a pair 105 of bushings 20 secured to the inner circumferential face of the tube 6 by means of rivets 21. The stator tube 2 is provided with a pair of orifices 22 and 23 diametrically opposite and in alignment with orifices 110

24 which extend through the sleeve extensions 19 of the bushings 20. The orifices 22 and 23 in the stator tube 2 and the orifices 24 in the bushings 20 are of the same size 5 and are in alignment, and they are adapted to receive sleeves 25 and 26 which are of a size to receive the supporting rod 16.

The bushings 19 of the rotor tube 6 are provided with tapped orifices 28 which are 10 adapted to receive screws 29 the ends of which pass through orifices 30 in the sleeves 25 and 26 to permit the same to engage the rod 16 to rigidly secure the rotor tube 6 to the rod 16. The sleeve extensions 19 of the 15 bushings 20 protrude through the diametrically opposite orifices 17 and 18 an equal distance so that the distance between the respective ends of the sleeve extensions 19 is approximately that of the inner diameter of 20 the stator tube 2, so that the ends of these sleeve extensions 19 when the rotor 6 is positioned in the stator tube 2 on the rod 16 engage the inner circumferential face of the stator tube 2 and prevent longitudinal movement 25 of the rotor tube 6 on the supporting rod 16. The rod 16 passes through the respective sleeves 25 and 26 associated with each of the other rotor tubes 7, 8 and 9, and these rotor tubes 7, 8 and 9 are secured to 30 the rod 16 by set screws 29 as described in connection with rotor tube 2 and as the rod 16 is rotated the rotor tubes 6, 7, 8 and 9 which are secured thereto by the set screws 29, are simultaneously rotated. The 35 transformers T, T', T² and T³ are of the 90 degree coupler type, so that the rotor tubes 6, 7, 8 and 9 may be rotated 90 degrees or until they are at right angles to the axis of the stator tubes 2, 3, 4 and 5.

40 A bracket 31 secured to the panel 32 by means of screws 33 which pass through suitable orifices in the panel 32 and extended portions 34 of the bracket 31 and have threaded engagement with nuts 35 which secures the bracket 31 to the panel 32. The bracket 31 extends rearwardly from the panel 32 between the transformers T' and T² and is provided with an integrally formed portion 36 extending upward at right angles 45 from the bracket 31 which is provided with an orifice through which the rod 16, which supports the rotor tubes 6, 7, 8 and 9 extends. A shaft 37 rotatably supported in integrally formed extended portions 38 and 39 of the bracket 31 has secured to its one end 37' a bevel gear 40 which meshes with a bevel gear 41 secured to the rod 16 by means of a set screw 42. Through the medium of the shaft 37 and the bevel gear 40 secured thereto and 50 the bevel gear 41 on the rod 16 simultaneous rotation of the shaft 37 and rod 16 is accomplished.

55 The other end 37² of the shaft 37 extends through an orifice in the panel 32 and has secured to its protruding end a graduated

dial D adapted to rotate the shaft 37 and through the medium of the gears 40 and 41 and rod 16 the rotor tubes 6, 7, 8 and 9 are rotated simultaneously. The dial D is provided with suitable graduations and a suitable mark is placed upon the front of the panel 32 to indicate the degree of rotation of the rotor elements. A stop pin 43 secured to the shaft 37 and angular extensions 44 on the bracket 31 cooperate to prevent excessive rotation of the shaft 37. A coil spring 45 is placed around the shaft 37 with one end resting against the extended portion 39 of the bracket 31 and its other end resting against a collar 46 adapted to be rigidly secured to the shaft 37 by means of a set screw 47. The collar 46 may be slid longitudinally along the shaft 37 to permit the tension or compression of the coil spring 45 to be adjusted and this spring 45 causes the bevel gear 40 on the shaft 37 to be held in mesh with the bevel gear 41 on the rod 16 to prevent any lost motion between the rod 16 and the shaft 37 and to also provide frictional means to maintain the rotor elements 90 in any adjusted position.

The stator coils SC, SC', SC² and SC³ are tapped and these taps are led to contacts 48 mounted on panels 49, 50, 51 and 52 and as all of the panels are of similar construction and arrangement the description of one will suffice for a clear explanation of all. The panel 49 associated with the stator coil SC is rectangular in shape and of suitable insulating material such as bakelite and is 100 provided with suitable orifices 53 equally spaced apart which are adapted to receive contacts 48. The contacts 48 are provided with reduced portions 48' which extend through the orifices 53 to which the taps or leads 54 from the tapped stator coil SC are fastened by suitable means such as solder. The contacts 48 are secured in the orifices 53 in the panel 49 in any suitable manner and are arranged in an arc of a circle, and a wiper arm 55 is adapted to pass over and engage the contacts 48. The wiper arms 55, 56, 57 and 58 are multiply controlled and adapted to be moved corresponding distances simultaneously, so that the inductances of the 110 transformers T, T', T² and T³ may be varied by placing a different number of turns of wire composing the secondaries of the transformers in circuit. By using a multiple control device the same number of turns will 115 be used on each coil, and thus the most efficient results with the simplest operation will be obtained and the means for accomplishing this will now be described.

The panel 49 associated with the transformer T is located forward of the same and is secured to the integrally formed angular extensions 59 and 60 of the U-shaped bracket 11 which supports the stator tube 2, by means of screws 75 which pass through 130

openings in the panel and have threaded engagement with tapped orifices in the extensions 59 and 60. Additional securing means for the panel 49 in the form of a bracket 61 is secured to the same by means of a rivet 62 and is provided with an integrally formed pin member 63 which extends through an orifice 64 in the stator tube 2 to rigidly secure the upper portion 10 of the panel 49 against movement. A bushing 65 provided with a reduced portion 66 is inserted into a suitable orifice 67 in the panel 49 and the reduced portion 66 in the orifice 67 extends slightly beyond the face of the 15 panel 49 and is upset or spun over to secure the bushing 65 to the panel. The bushing 65 is provided with a central orifice 68 which is adapted to receive a stub shaft 69 which extends through this orifice 68, and the protruding end 69' of the shaft 69 has a portion 20 cut away to form a flat face 70. A bushing 72 is provided with a circular orifice 73 in its one end and with an orifice 74 in its other end shaped to conform with the formed end 25 69' of the shaft 69 which extends into this shaped orifice 74. The end 69' of the shaft 69 protrudes slightly into the circular orifice 73 of the bushing 72 and this protruding end is staked over to secure this bushing 72 to 30 the shaft end 69'.

A shaft 80 extends through an orifice 81 in the front panel 32 into the orifice 73 in the bushing 72, and a set screw 82 having threaded engagement with a suitable tapped orifice in the bushing 72 engages this shaft 80 to rigidly secure the same in the bushing 72. The wiper 55 is provided with a dished portion 55' having an orifice 71 of a size and shape to fit over the formed end 69' 35 of the shaft 69 and this dished portion 55' of the wiper 55 when positioned on the stub shaft 69 rests between the bushing 65 in the panel 49 and the face of an arm 76 secured to the bushing 72. It is readily apparent 40 that as the shaft 80 is turned through the medium of a knob K secured to the end protruding through the panel 32 the bushing 72 and the stub shaft 69 secured to the bushing 72 and the wiper 55 which is supported on the stub shaft 69 are rotated as a 45 whole causing the free end 55' of the wiper 55 to engage successive contacts 48, as it is rotated from left to right and vice versa, though the medium of the shaft 80. The 50 arm 76 secured to the bushing 72 is also rotated and this movement of the arm 76 is for purposes as will presently be described. A bracket 85 secured to the panel 49 by the screws 75 is provided with an upwardly extended portion provided with an orifice 86 through which the shaft 80 extends and serves as a bearing when the same is rotated 55 and the bushing 65 secured to the panel 49 and through which the stub shaft 69 extends serves as a bearing for the shaft 69

when it is rotated through the agency of the shaft 80 as just described. To prevent any overrun of the free end 55' of the wiper 55 as it passes from one contact 48 to the next and also produce a snap action as the 70 wiper 55 passes from one contact 48 to the next, the arm 76 is provided with a downwardly extending portion 76' provided with a plurality of notches 86 in its arcuate shaped edge equal in number to the contacts 75 48 secured to the panel 49.

The bracket 85 secured to the plate 49 as already described is provided with an orifice 87 which is adapted to receive a ball bearing 88. A leaf spring 89 secured at its one end 80 to the bottom face of the bracket 85 has its free end engaging the ball bearing 88 which rests in the orifice 87 to maintain the ball bearing 88 in engagement with the notches 86 in the arm 76. The ball bearing 88 operates with the notches in the extended portion 76' of the arm 76 and as the shaft 80 is rotated the arm 76 also rotates causing a tooth 90 formed by two adjacent notches 86 to engage the ball bearing 88 and force 90 it down against the normal tension of the spring 89 and as the arm continues its rotation the ball 88 passes the tooth 90 and acts upon the next notch 86 under the influence of the spring 89 so as to give a quick snap 95 action to the wiper 55 and arm 76 as the wiper 55 passes from one contact to the next.

The wipers 56, 57 and 58 associated with the transformers T', T² and T³ are rotatably supported in a manner similar to that described in connection with the wiper 55 of the transformer T and a description of one will suffice to give a clear understanding of all. The bushing 91 is secured to the panel 50 by staking its protruding end and is provided with a central orifice 92 which receives a stub shaft 93. The stub shaft 93 is provided with a flat portion 94 and the wiper 56 and arm 77 are provided with orifices shaped to permit them being slipped on the 100 end 93' of the stub shaft 93, and the end of the stub shaft 93 protruding slightly beyond the face of the arm 77 is staked over to secure the wiper 56 and arm 77 to the stub shaft 93. The wipers 57 and 58 and arms 105 78 and 79 associated with the transformers T² and T³ are secured to stub shafts 95 and 96 in a similar manner and the wipers 55, 56, 57 and 58 and arms 76, 77, 78 and 79 are rotated simultaneously through means to be 110 presently described.

A link 100 provided with a bifurcated end 101 is associated with the free ends of each of the arms 76, 77, 78 and 79 and straddle the same and are pivotally secured thereto 115 by means of pivot pins 102. Each link 100 is provided with an orifice 103 which is adapted to receive a rod 104. Set screws 105 having threaded engagement with suitable tapped orifices in the ends of the links 120

- 100 engage the rod 104 to rigidly secure the rod 104 to the links 100 to connect the rod 104 with the arms 76, 77, 78 and 79 associated with the wipers 55, 56, 57 and 58.
- 5 It is readily apparent that when the shaft 80 is rotated through the agency of the knob K secured to the same, the arm 76 secured to the bushing 72 to which the shaft 80 is secured is rotated, and through the 10 agency of the links 100 which connect the arms 76, 77, 78 and 79 to the connecting rod 104 the movement of the arm 76 is transmitted to the arms 77, 78 and 79 to simultaneously move them.
- 15 The arms 76, 77, 78 and 79 are provided with depending legs 106 which are so spaced apart as to span the wipers 55, 56, 57, and 58. The arm 76 is associated with the stub shaft 69 as before described, and as the 20 arms 77, 78 and 79 are secured to the stub shafts 93, 95 and 96 as before described the movement of the arms causes rotation of the stub shafts 93, 95 and 96. The wipers 55, 56, 57 and 58 are secured to the stub 25 shafts and as the stub shafts are rotated by the arms secured thereto the wipers 55, 56, 57 and 58 also move to cause the free ends of the wipers to move from one contact to the next. A pair of stop pins 110 secured 30 to each of the panels 49, 50, 51 and 52 are provided to limit the movement of the wipers from left to right and vice versa, these stops 110 of course being engaged by the respective edges of the arms 76, 77, 78 and 35 79.
- Terminals 111 secured to the stator tubes 2, 3, 4, and 5 provide means for securing the terminals of the windings of the stator coils SC and also provide means for connecting the external conductors of an electrical circuit. A pair of terminals 112 secured to the stator tubes 2, 3, 4 and 5 by means of screws 113 and nuts 114 are provided with integrally formed parallel spring 40 arms 115 the free ends of which engage respectively the sleeves 25 and 26 which extend into the bushings 20 which support rotor tubes 6, 7, 8 and 9 on the rod 16. The bushings 20 are provided with integrally 45 formed terminals 116 to which the terminal windings of the rotor coil RC are secured. The bushings 20 and sleeves 25 and 26 which extend into the bushings 20 are made of suitable conducting material and contact 50 each other so that the winding terminals of the rotor coil RC are provided with a conducting path including the respective bushings 20 and sleeves 25 and 26 and the arms 115 of the respective terminals 112 secured 55 to the stator tubes. External conductors may be secured to the terminals 112 and thus connect the terminal windings of the rotor coils RC to an external circuit.
- The wipers are provided with integrally 60 formed dished semicircular portions 55³, 56³, 57² and 58² and are split into sections 120 which are bent down to engage disks 121 which are provided with orifices of a size to fit on the reduced portions of the bushings secured to the panels 49, 50, 51 and 52. 70 The disks 121 are provided with extended portions 122 which are secured to the panels by means of suitable screws and are so formed that when the disks 121 are positioned on the bushings between the face of 75 the panels and the bent sections 120 of the wipers the same are placed under tension to firmly engage these portions 120 of the wipers to provide rubbing contacts between the disks 55³, 56³, 57² and 58² and the wipers. 80 The extended portions 122 of the disks 121 are associated with terminals 124 to which external conductors are connected and through the agency of the extensions 122 and the disks 121 which are in contactual 85 engagement with the wiper disks current is thus carried to the wipers.
- The respective transformers T, T', T² and T³ are shielded and for this purpose I provide containers or shields C, C', C² and C³ 90 constructed of suitable metal such as copper and as each one is of similar construction a description of one will suffice. The container C comprises a base 125 secured to the subpanel 10 by means of screws 11' which 95 also secure the brackets 11 to the base board 10. A suitable strip of insulation 126 is placed between the bracket 11 and the base 125 to insulate the bracket 11 from the base 125. The base 125 is provided with up- 100 turned edges 126' and a square shaped tube or shell 127 is adapted to surround the transformer T and rests on the base 125 inside of the upturned edges 126 of the same. The opposite walls 128 and 129 of the shell 127 105 are provided with aligned oblong slots 130 through which the rod 16 which supports the rotor elements R, R', R² and R³ extends. Aligned oblong orifices 131 in the opposite walls 128 and 129 permit the passage of the 110 rod 104 which connects the arms 76, 77, 78 and 79 together. A cover 132 with depending edges 133 sets on the shell 127, and with the shell 127 and base 125 as a whole form a container or shield C for the transformer 115 T. A rod 134 secured to sub panel 10 by means of nuts 135 extends upward between the containers C and C' and a spring clamping member 136 provided with an orifice through which the rod 134 extends engages 120 the covers 132 of the respective containers or shields C and C'. A nut 137 having threaded engagement with the end of the rod 134 is turned down against the clamping member 136 to place the same under tension to hold the cover and shell in position against movement. The shield C in addition is provided with a slot 140 through which the bracket 85 and shaft 80 extend. The 125 containers or shields C', C² and C³ are of 130

similar construction and the containers C² and C³ are also maintained in position by means of a rod 141 and clamping member 142. The shields C, C', C² and C³ shield the 5 transformers T, T', T² and T³ as is well understood.

The knob K is rotated to change the inductance of the windings in comparatively coarse steps while the dial D operates to 10 vary the inductance of the secondaries within the steps of inductance between the taps.

The bevel gears which connect the shaft 16 to the shaft 37 have a 2 to 1 ratio so that the dial D moves 180 degrees for a 90 15 degree movement of the rotor elements. By this method a fine adjustment of the rotor elements may be made for a coarser adjustment of the dial D.

While I have described a preferred embodiment of my invention I do not however wish to be limited to the exact structure as shown but aim to cover all that comes within the spirit and scope of the appended 20 claims.

Having described my invention what I claim is new and desire to secure by Letters Patent of the United States is:

1. A device of the character described including a transformer, a stator element and 30 a rotor element for said transformers, a rotatable shaft for supporting the said rotor element, a pair of bushings secured to said rotor element, sleeve members extending through said bushings and said stator element, said shaft extending through said sleeves, and means in said bushings extending through said sleeves and engaging said shaft to rigidly secure said rotor element to 35 said shaft.

2. A device of the character described including a transformer comprising a stator element and a rotor element, a pair of bushings secured to said rotor element, sleeve members extending through said bushings and aligned orifices in said stator element, a shaft extending through said sleeves, and screw means in said bushings extending through said sleeves and engaging said shaft to rigidly secure said rotor element to 45 said shaft.

3. A device of the character described including a transformer comprising a stator element and a rotor element, a pair of bushings diametrically opposite and secured to 50 said rotor element, sleeve members extending through said bushings and aligned orifices in said stator element, a shaft extending through said sleeves, set screws in said bushings extending through aligned orifices in said sleeves and engaging said shaft to 55 rigidly secure said rotor element to said shaft, said rotor element being capable of rotating through a predetermined angle within said stator element.

4. A device of the character described in-

cluding a transformer comprising a stator element and a rotor element, a pair of bushings diametrically opposite each other and secured to said rotor element, a winding on 70 said rotor element, terminals integrally formed with said bushings adapted to receive the terminal ends of said winding, sleeve members extending through said bushings and aligned orifices in said stator element, a shaft extending through said sleeves, 75 screw means in said bushings extending through said sleeves and engaging said shaft to rigidly secure said rotor element to said shaft, and terminal means secured to said stator element and engaging said sleeves to 80 conductively extend said terminal ends of said rotor winding to said terminal means.

5. A device of the character described including a transformer comprising a stator element and a rotor element, a pair of bushings diametrically opposite each other and secured to said rotor element, a winding on 85 said rotor element, terminals integrally formed with said bushings adapted to receive the terminal ends of said winding, 90 sleeve members extending through said bushings and aligned orifices in said stator element, a shaft extending through said sleeves, set screws in said bushings extending through said sleeves and engaging said shaft to rigidly secure said rotor element to 95 said shaft, terminals secured to said stator element, and extending arms integrally formed with said terminals and engaging said sleeves to conductively connect said 100 terminal ends of said rotor winding with said terminals on said stator element to permit the same to be connected to an external circuit.

6. A device of the character described including a plurality of transformers comprising stator and rotor elements, a pair of bushings for each said rotor elements diametrically opposite each other and secured to said rotor elements, sleeve members extending through said bushings and aligned orifices in said stator elements, a shaft extending through the aligned sleeves, set screws in said bushings extending through orifices in said sleeves and engaging said 105 shaft to rigidly secure said rotor elements to said shaft, and means for simultaneously 110 rotating said rotor elements a predetermined degree within said stator elements.

7. A device of the character described including a plurality of transformers comprising stator and rotor elements, a pair of bushings for each of said rotor elements diametrically opposite each other and secured to said rotor elements, sleeve members 115 extending through said bushings and aligned orifices in said stator elements, a shaft extending through said aligned sleeves, set screws in said bushings extending through orifices in said sleeves and engaging said 120 shaft to rigidly secure said rotor elements to said shaft, and means for simultaneously rotating said rotor elements a predetermined degree within said stator elements.

125

ing said shaft to rigidly secure said rotor elements to said shaft, a second rotatable shaft mounted at an angle to said first shaft, a gear for each of said shafts for 5 transmitting movement from one of said shafts to the other to simultaneously rotate said rotor elements within said stator elements.

8. A device of the character described, including a plurality of transformers comprising stator and rotor elements, a pair of bushings for each rotor element diametrically opposite each other and secured to said rotor elements, sleeve members extending 10 through said bushings and aligned orifices in said stator elements, a shaft extending through said aligned sleeves, set screws in said bushings to rigidly secure said rotor elements to said shaft, a second rotatable 15 shaft and a bracket for supporting said second shaft, said second shaft mounted at right angles to said first shaft, a gear for each of said shafts for transmitting movement from said second shaft to said first 20 shaft to simultaneously rotate said rotor elements within said stator elements, and means on said second shaft and said bracket for limiting the rotation of said rotor elements.

30 9. A device of the character described including a supporting member, a coil support connected thereto and having an orifice located near its edge, a contact plate connected to said supporting member, and an angular 35 member having one end secured to said contact plate and its other end entering said orifice in said supporting member for maintaining said contact plate in position relative to said coil supporting member.

40 10. A device of the character described including a supporting member, a coil support connected thereto, a contact plate connected to said supporting member, an angular member having one end secured to said 45 contact plate and its other end entering a slot in said coil supporting member for maintaining said contact plate in position relative to said coil supporting member, contacts secured to said contact plate, a 50 wiper secured to said contact plate for cooperation with said contacts, and a second coil support mounted within said first coil support.

55 11. A device of the character described including a supporting member, a coil support connected thereto, a contact plate connected to said supporting member, a member connecting said contact plate to said coil supporting member, contacts secured to said contact plate, a wiper secured to said contact plate for cooperation with said contacts, a second coil support mounted within said first coil support, commutator members connected to said second coil support adapted for rotation therewith, and contact fingers on said

first coil support for cooperation with said commutator members.

12. A device of the character described including a base member, a stationary and a rotor coil support, said rotor coil support 70 being rotatably mounted in said stationary coil support, a supporting member secured to said base member and supporting said stationary coil support, a contact panel secured to said supporting member, and additional means comprising an angular member having one end secured to said contact panel and the other end engaging a slot in said coil supporting member for maintaining said contact panel in position relative 80 to said stationary coil support.

13. A device of the character described, including a base member, a plurality of stator coil supports secured thereto, said stator coil supports being mounted in parallel lines 85 and at right angles to said base, rotor coil supports mounted within said stator coil supports, a shaft extending lengthwise of said base member and through the sides of said stator coil supports, a pair of bushings 90 secured to said rotor coil supports and surrounding said shaft, and screw means in said bushings adapted to engage said shaft to rotatably support said rotor coil supports.

14. A device of the character described, including a base member, a plurality of stator coil supports secured thereto, said stator coil supports being mounted in parallel lines and at right angles to said base, rotor coil supports mounted within said stator coil 100 supports, a shaft extending lengthwise of said base member and through the sides of said stator coil supports to rotatably support said rotor coil supports, contact plates associated with and operatively connected 105 to the stator coil supports, contact wipers for each of said contact plates, pivoted control members associated with each of said wipers, and a shaft extending lengthwise of said base secured to said pivoted control 110 members for controlling said contact wipers.

15. A device of the character described, including a base member, a plurality of stator coil supports secured thereto, said stator coil supports being mounted in parallel lines 115 and at right angles to said base, rotor coil supports mounted within said stator coil supports, a shaft extending lengthwise of said base member and through the sides of said stator coil supports to rotatably support said rotor coil supports, contact plates associated with and operatively connected 120 to said stator coil supports, contact wipers for each of said contact plates, pivoted control members associated with each of said wipers, a shaft extending lengthwise of said base secured to said pivoted control members for controlling said contact wipers, a shaft mounted at right angles to the shaft 125 which controls the rotor coil supports for 130

controlling the same, and a second shaft for controlling the movement of said shaft associated with said contact wipers.

16. A device of the character described including a stator coil support, a rotor coil support adapted to be mounted within said stator coil support, means secured to said rotor coil supports and engaging the inner periphery of said stator coil supports for limiting longitudinal movement of said rotor coil supports, means extending through said first means and orifices in said stator coil supports for rotatably mounting said rotor coil support, and a controlling rod extending through said first means for rotating said rotor coil support.

17. A device of the character described including a stator coil support, a rotor coil support adapted to be mounted within said stator coil support, means secured to said rotor coil support engaging the inner periphery of said rotor coil support for limiting longitudinal movement of said rotor coil support, means extending through said first means and orifices in said stator coil supports for rotatably mounting said rotor coil support, a controlling rod extending through said first means for rotating said rotor coil support, and spring means cooperating with said last means for effecting electrical contact therewith.

18. A device of the character described including a plurality of contact plates, wipers rotatably supported by said contact plates, wiper control members, control devices pivotally secured to said wiper control members, and a rod extending through said control devices for effecting operation of said contact wipers.

19. A device of the character described including a plurality of contact plates, wipers rotatably supported by said contact plates, wiper control members, control devices pivotally secured to said wiper control members, a rod extending through said control devices for effecting operation of said contact wipers, and means for moving said rod to simultaneously control said contact wipers.

20. A device of the character described including a supporting member, a coil support connected thereto, a contact plate connected to said supporting member, and an angular member having one end secured to said contact plate and its other end entering a slot in said coil support for maintaining said contact plate in position relative to said coil supporting member, and a metal housing member for said coil support.

21. A device of the character described including a base member, a stationary and a rotor coil support, said rotor coil support being rotatably mounted in said stationary coil support, a supporting member secured to said base member and supporting said

stationary coil support, a contact panel secured to said supporting member, and additional means comprising an angular member having one end secured to said contact panel and its other end entering a slot in said stationary coil support for maintaining said contact panel in position relative to said stationary coil support, and a metal housing member enclosing said stationary coil support and said panel.

22. A device of the character described, including a base member, a plurality of stator coil supports secured thereto, said stator coil supports being mounted in parallel lines and at right angles to said base, rotor coil supports mounted within said stator coil supports, a shaft extending lengthwise of said base member and through the sides of said stator coil supports to rotatably support said coil supports, contact plates associated with and operatively connected to the stator coil supports, contact wipers for each of said contact plates, pivoted control members associated with each of said wipers, and a shaft extending lengthwise of said base secured to said pivoted control members for controlling said contact wipers, and metal housing members for said stator coil supports and contact plates provided with orifices for shafts.

23. A device of the character described including a stator coil support, a rotor coil support adapted to be mounted within said stator coil support, means secured to said rotor coil supports and engaging the inner periphery of said stator coil supports for limiting longitudinal movement of said rotor coil supports, and means extending through said first means and orifices in said stator coil support for rotatably mounting said rotor coil support, and a metal housing shield enclosing said stator coil supports and provided with an orifice through which said last means extends, said housing shield comprising a base portion having upturned edges, side member adapted to fit within said upturned edges and a cover portion having edges adapted to surround said side member and means for maintaining said members in position to form a unit structure.

24. A device of the character described, including a base member, a plurality of stator coil supports secured thereto, said stator coil supports being mounted in parallel lines and at right angles to said base, rotor coil supports mounted within said stator coil supports, a shaft extending lengthwise of said base member and through the sides of said stator coil supports to rotatably support said rotor coil supports, contact plates associated with and operatively connected to said stator coil supports, contact wipers for each of said contact plates, pivoted control members associated with each of said wipers,

- ers, a shaft extending lengthwise of said base secured to said pivoted control members for controlling said contact wipers, a shaft mounted at right angles to the shaft which 5 controls the rotor coil supports for controlling the same, and a second shaft for controlling the movement of said shaft associated with said contact wipers, and metal housing shields enclosing said stator coil supports and said contact plates provided 10 with orifices through which said first shaft and/or said shaft extends.
25. A device of the character described including a supporting member, a coil sup-
- port connected thereto, a contact plate connected to said supporting member, and an angular member having one of its ends secured to said contact plate and its other entering a slot in said coil support for maintaining said contact plate in position relative to said coil supporting member, and a metal housing member for said coil support, and yielding means for holding a cover on said metal housing member. 15 20 25

In testimony whereof I have signed this specification.

ERNEST A. BOHLMAN.
